OIL WELL PUMP

Luther B. Rowsey, Houston, Tex.

Application December 29, 1941, Serial No. 424,701

11 Claims. (Cl. 103—202)

This invention relates to pumps for deep wells, and more particularly to a construction and technique for protecting the pump plunger of tubing pumps from damage while moving the same during the lowering thereof to or withdrawing it from the working barrel of the pump.

In the so-called tubing pumps which are commonly used for lifting fluids within wells, a plunger which is provided with a traveling valve is lowered through the tubing to the pump barrel which comprises a part of the tubing string. Cups or other sealing means are provided on the plunger to form a seal with the walls of the pump barrel so that upward strokes of the plunger and valve are effective for lifting fluid within the tubing. When a plunger is to be repaired or replaced, it is customary, if possible, to withdraw the sucker rod string and plunger through the tubing to the surface without a removal of the tubing from the well bore. When the desired repair or replacement has been effected the plunger assembly and sucker rod string are again lowered in the tubing until the plunger assembly has reached its operating position within the pump barrel.

When a repaired or a new plunger is lowered into a tubing string any metallic projection, such as metal slivers, will score one or more of the plunger cups or packing, and such damage may actually prevent operation of the pump or may be the source of incipient failure after a limited period of operation.

Also, when the plunger is removed by being lifted within the tubing, a superposed column of fluid is lifted and the pressure produced thereby tends to force the cups, or other packing, outwardly and into each annular groove formed by the ends of the tubing sections and the associated couplings. Hence damage is inflicted upon the sealing means during the entire upward trip and pieces are torn therefrom and fall into the tubing whence such pieces subsequently enter the pump valves and hence constitute a menace to efficient pumping operations.

Occasionally sucker rods break during pumping operations and under such circumstances connection is effected with the broken end by a fishing tool. This end and the plunger assembly are elevated and, since the plunger is subjected to the hazards above indicated, the complete assembly is usually removed, as it is assumed that the cups or other packing have been destroyed and must be replaced prior to lowering the assembly again to pumping position. The present invention contemplates a construction

and technique whereby it is possible merely to lift the broken end to the surface, attach the upper portion of the sucker rod thereto and then lower the assembly to pumping position.

5 It is the primary object of the invention to provide a pumping mechanism whereby the above mentioned difficulties are eliminated.

Another object is to provide in a pump a plunger shield for protecting the plunger assembly during its travel to or from the pump barrel.

10 Still another object is to provide a construction whereby the plunger assembly may be lifted any desired distance in the well for connection of a sucker rod thereto and thence lowered to the previous operating position for continued operation.

15 A further object is to provide a plunger shield for protecting an assembly during travel within a tubing string.

20 A still further object is to provide in an oil well pump a plunger shield which is capable of effectively removing paraffin from the interior of the tube during movement of the shield therein.

25 It is also an object to provide a tubular plunger shield having flexible longitudinal segments possessing sufficient outward tension to effect thorough cleaning of the walls of the tubing.

Another object is to provide a plunger shield having a normally expanded end portion adapted 30 to freely receive the plunger to be protected thereby.

35 A still further object is to provide in an oil well pump a plunger shield which is so constructed that an end portion thereof is contracted during travel within the tubing.

The foregoing objects together with further objects will be more fully apparent from the following description taken in connection with the accompanying drawing in which:

40 Fig. 1 is a sectional view through a well pump installation showing the plunger assembly closely adjacent the upper end of the pump barrel and within the plunger shield;

45 Fig. 2 is a sectional view showing the shield in position in the well and the plunger assembly exteriorly of the shield and within the pump barrel;

50 Fig. 3 is an elevational view of one form of shield provided with a sand-relieving groove;

55 Fig. 4 is an elevational view of a shield which is provided with flexible segments at both the upper and lower ends of the shield.

In Fig. 1 of the drawing there is shown a tubing string 1 having conventional tube sections 2 and 3 interconnected by means of a collar 4,

there being a slight gap at 5 between these sections. At a desired location within the well there is provided the pump barrel 6 which is of slightly smaller internal diameter than that of the tubing 1 and which has a carefully prepared inner surface to facilitate movements of and to resist wear by the pump plunger assembly 7 therein. The coupling 8 interconnects the member 3 and the barrel 6 and has an internal groove 9 which supplements in performing the function which will more fully appear.

The pump plunger 7 is of any well known design and includes cups 15 and a traveling valve 16. This assembly is attached to the lower end of the sucker rod 17 which is utilized to move the plunger assembly to and from position within the barrel 6, and also to reciprocate such assembly during pumping operations.

In Fig. 1 the assembly is shown proximate the upper end of the barrel 6, and when in this position, the plunger assembly 7 is encased within a shield 20. This shield comprises a tubular member of relatively thin material and has an inwardly extending flange 21 at its upper end so that the plunger assembly cannot slip outwardly from within the shield.

The lower end of the shield 20 is provided with slots 22 and the intermediate segments 23 are tensioned in a manner that they normally tend to move outwardly slightly so that no difficulty is experienced in causing the assembly 7 to enter the shield whether such assembly be in position proximate the upper end of the barrel 6 in the well or outside the tubing string 1.

Attention is also directed to the fact that the segments 23 are thickened at 24 at their lower ends and that they are tapered inwardly at 25 so that a relatively sharp edge 26 is formed. This construction is designed to serve additional functions. For example, when a shield and plunger assembly are within the tubing 1, the segments 23 are constantly urged outwardly into engagement with the side walls of the tubing so that paraffin or other material adhering to the walls of the tubing is removed therefrom. Also, as is apparent from the drawing, the thickened portion 24 causes the lower ends of the segments 23 to be forced inwardly whereby the internal bore of the shield proximate its lower end is tapered, and hence offers a restriction to movement of the assembly 7 from within the shield.

The thickened portions 24 are of such lineal extent that they will not enter the coupling gaps 5 in the tubing and hence the conditions just described exist at all times during the travel of the assembly in the tubing 1. When, however, the assembly 7 is lowered to the upper end of the barrel 6, the thickened portions 24 enter the gap between the ends of the section 3 and the barrel 6, such gap including the internal groove 9 in the coupling 8. This condition is illustrated in Fig. 2. When the shield 20 has reached this position the segments 23 move outwardly and the downward movement of the shield is arrested by its engagement with the lower shoulder in the groove 9 or with the upper end of the barrel 6. It seems apparent that the plunger assembly 7 is then free to move outwardly from within the shield 20 and into the barrel 6 so that the respective parts are in the positions shown in Fig. 2.

The operation of the construction seems apparent from the foregoing description. By way of summary, it may be stated that the installation of the plunger within the barrel 6 is effected

by first placing the shield 20 about the plunger assembly. The segments 23 are then pressed inwardly so that the assembly and shield will enter the tubing 1 whence these elements are lowered upon the sucker rod string 17. As already explained, the lineal extent of the portions 24 is sufficient that the segments 23 are urged inwardly at all times during the travel of the assembly and shield within the tubing.

When the shield reaches the position shown in Fig. 2, the plunger assembly moves outwardly, as just described, into the pump barrel 6 and thereafter pumping operations are carried out in a normal manner.

If it be desired to elevate or remove a plunger assembly from within the well, the sucker rod string 17 is lifted and as the plunger assembly 7 leaves the barrel 6 such assembly enters the shield 20. When the assembly reaches the upper end of the shield a lifting effort is produced thereon and by virtue of the upper tapered surface 27 on the thickened portions 24, the segments 23 are again urged inwardly during the upward travel of the assembly and shield. If the plunger assembly 7 is merely to be lifted within the tubing and then returned to pumping position, it seems apparent that this operation can be effected since the shield 20 will move downwardly at any time the sucker rod string 17 is lowered and in this manner the assembly 7 is at all times protected by the shield 20.

Under some circumstances there is a tendency for sand or other material within the liquid column in the tubing string 1 to settle and tend to clog the tubing above the shield 20. To avoid difficulty by such sedimentation, a groove 28 may be provided at the upper end of the shield 20, as illustrated in Fig. 3, it being intended that the clogging material be bypassed through this groove by flushing action of liquid longitudinally of the shield 20.

In Figs. 1 and 3 the shield is shown as provided with a leading edge 26 at its lower end to assist in removing paraffin or other material from the walls of the tubing as the shield is lowered therein. Frequently it is desired that a similar operation be performed as the shield and assembly are lifted within the well. To this end, the shield 20 may be provided with similar upper segments 23', as shown in Fig. 4, such segments also including thickened areas 24' terminating in an inner tapered surface 25' and leading edge 26'. Since the thickened portions 24' are effective to urge the segments 23' inwardly, it is apparent that the shield 20 necessarily moves with the plunger during its travel within the tubing 1, except when the shield is moved to the position shown in Fig. 2 or has been withdrawn from the upper end of the tubing 1.

While the invention as illustrated includes a pump plunger provided with plunger cups, it is to be understood that the invention is not confined thereto but comprehends utilization of any type of traveling valve and plunger construction used in so-called tubing pumps. Broadly, the invention comprehends a novel construction and technique for protecting a pump plunger from damage during movement within a string of tubing.

What is claimed is:

1. A well pump including a flow tubing, a pump barrel attached thereto, a pump plunger in said barrel, and a plunger shield in the tubing at the upper end of the barrel said shield being a substantially tubular structure adapted to surround

the plunger and into and out of which the plunger can move, the lower end of said shield comprising segments tensioned to move resiliently outwardly toward the walls of the tubing so that the plunger enters the shield when the former is moved upwardly from within the pump barrel.

2. A well pump including a flow tubing, a pump barrel attached thereto, a pump plunger in said barrel, a plunger shield in the tubing at the upper end of the barrel said shield being a substantially tubular structure adapted to surround the plunger and into and out of which the plunger can move, the lower end of said shield comprising segments tensioned to move resiliently outwardly toward the walls of the tubing, and means for releasably holding the shield proximate the upper end of the barrel so that the pump plunger may move to and from the interior of the shield.

3. A well pump including a flow tubing, a pump barrel attached thereto, a pump plunger in said barrel, and a tubular plunger shield in the tubing proximate the barrel adapted to receive the plunger moving outwardly from within the barrel, the lower end of said shield comprising segments normally urged resiliently outwardly into engagement with the walls of the tubing.

4. A well pump including a flow tubing, a pump barrel attached thereto, a pump plunger in said barrel, and a tubular plunger shield in the tubing proximate the barrel adapted to receive the plunger moving outwardly from within the barrel, the lower end of said shield comprising segments normally urged resiliently outwardly into engagement with the walls of the tubing, said segments having outwardly extending projections at their lower ends adapted to urge the segments inwardly during movement of the shield and plunger within the tubing.

5. A well pump comprising a flow tubing, a pump barrel, means interconnecting the tubing and barrel to provide an internal recess therebetween, a plunger in the barrel, a plunger shield in the tubing, said shield comprising an elongated hollow member into and from which the plunger may move and including a resiliently expandable portion, and means on said portion adapted to enter said recess to releasably hold the shield in position to receive the plunger moving from within the barrel.

6. A well pump comprising a flow tubing, a pump barrel, means interconnecting the tubing and barrel to provide an internal recess therebetween, a plunger in the barrel, a plunger shield

in the tubing, said shield comprising an elongated hollow member into and from which the plunger may move and including a resiliently expandable portion, and means on said portion adapted to enter said recess to releasably hold the shield in position to receive the plunger moving from within the barrel, said last mentioned means being adapted to pass slidably past the coupling gaps in the tubing string.

10. 7. A well pump comprising a flow tubing, a pump barrel, means interconnecting the tubing and barrel to provide an internal recess therebetween, a plunger in the barrel, a plunger shield in the tubing, said shield comprising an elongated hollow member into and from which the plunger may move and including a resiliently expandable portion, and means on said portion adapted to enter said recess to releasably hold the shield in position to receive the plunger moving from within the barrel, said last mentioned means comprising outwardly extending areas on the expandable portion adapted to pass slidably over the coupling gaps in the tubing string.

15. 8. A plunger shield adapted to surround a well pump plunger assembly during movement into and out of the well tubing string, comprising a tubular member, slots in one end of said member to form resilient segments normally expanded outwardly.

30. 9. A plunger shield adapted to surround a pump plunger assembly during movement of such assembly into and out of the well, a tubing string including a tubular member, oppositely extending slots in said member forming segmented ends thereon, and projections on certain of the segments of said ends engageable peripherally with the well tubing to force the segments inwardly.

35. 10. A well pump plunger shield comprising an elongated hollow member open at both ends, one end of said member being resiliently expandable to provide an enlarged opening to the interior of the member.

40. 11. A well plunger shield to enclose and protect the plunger as it is moved in the well comprising an elongated hollow member open at both ends, one end of said member being resiliently expandable to provide an enlarged opening to the interior of the member, and means on the expandable end for causing contracting of said end to a smaller size than the nominal cross section of the remainder of the member.
